SHOE CONSTRUCTION

John Lawandus, Buffalo, N. Y.

Application June 10, 1939, Serial No. 278,566

8 Claims. (Cl. 36—8.5)

This invention relates to shoe construction, and more particularly to a corrective insole which may be built in the shoe, and on which the foot of a wearer is directly supported.

One of the principal objects of this invention is to provide a stiff but flexible insole of such a nature that the longitudinal arch of the foot is adequately supported at all times, and the foot is not permitted to elongate unduly in standing or walking.

Another object is to provide an insole which will retain the heel of the foot and thus prevent its moving forward relative to the insole.

A still further object resides in the provision of a raised or convexed portion on an insole, which portion is arranged to preserve the shape of the metatarsal arch.

It is another object of the invention to provide an insole or the like with means for elevating the forward end of the os calcis, so as to prevent its rotation and deformation of the inner longitudinal arch.

A general object of the invention to be described is to provide a shoe with an inner sole which will place the foot in proper balance.

Among the other specific purposes of this invention is the provision of an insole for shoes which will eliminate objectionable friction between the foot and shoe due to the improper flattening of the longitudinal arch and forward sliding movement of the foot generally.

It is also an object to provide a corrective insole combination for use in shoes of the usual types, either as an insert or as an integral part of the shoe construction.

The foregoing and other objects of the invention, details of construction, and advantages will appear in the ensuing detailed description, when taken in connection with the accompanying drawings which illustrate a preferred improvement and one modification.

Referring to the drawings:

Fig. 1 is a perspective view of the insole assembly as seen from its inner side, and including a dotted showing of the bone structure of a foot;

Fig. 2 is a longitudinal section, taken on the line A—A of Fig. 1;

Fig. 3 is a transverse section along the line B—B of Fig. 1;

Fig. 4 is a further transverse section, along the line C—C of Fig. 1;

Fig. 5 is an additional transverse section, along the line D—D of Fig. 1;

Fig. 6 is a bottom plan of the insole of Fig. 1;

Fig. 7 is a side perspective view of a heel lift which is embodied in the insole construction; and

Fig. 8 is a longitudinal section of a shoe having the insole assembled therein, and indicating a modification.

Attention is called preliminarily to the principal or inner longitudinal arch LA indicated in Fig. 1, and to the anterior transverse or metatarsal arch MA marked on the same figure.

A complete insole 10, preferably of a moldable material such as leather, has a sheet member or lining 12 secured by suitable means, such as the rows 14, 16 of edge stitching, to the underside of the insole 10 so as to cover substantially the entire shank and a portion of the heel of the latter. An adhesive 18 may be used in combination with the stitches 14, 16. It will be observed that the member 12 has a forwardly extending head portion 13 the purpose of which will be described.

As illustrated, the insole 10 preferably has a normal outline and is of substantially uniform thickness in order to permit the economy of using a sole blank of ordinary form.

The upper surface of the heel portion of the insole 10 may be cupped somewhat, as at 20. The retaining action of the cupped portion 20 on the heel of a user is combined with the os calcis rotating action of a wedge-shaped heel lift 22, which may be secured adhesively to the underside of the insole 10 and extends from the inner edge of the heel of said insole and from under the middle of its shank to the end of the heel. The tapered or skived edge 24 of the lift 22 runs diagonally in a generally concave curve from the outer rear edge of the heel of insole 10, so that lift 22 lies almost completely inward of the longitudinal axis of the insole 10. While leather possesses some resilience, it is preferred to fashion the heel lift 22 from more yielding rubber. Note is taken that the lift 22 is intermediate member 12 and the insole 10, with the row of stitching 14 passing through all three.

In order to give the insole 10 a longitudinally arched shape in the shank area where it underlies the longitudinal arch of a foot, a shank member 24 comprising a steel shank stiffener 26, longitudinally arched or convexed upwardly, a shank piece 28, and a resilient pad 30 are secured together and retained between insole 10 and member 12. Where a more flexible shank member 24 is desired, molded rubber or leather can be substituted for spring steel.

From what has been said, it will be understood

that the function of the steel shank stiffener 26 is to limit resiliently the downward flexing of the upwardly arched portion of insole 10, and thereby to inhibit the undesirable flattening of the longitudinal arch and elongation of the foot.

Fastening means, such as a nail 32, may be used to secure shank stiffener 26 by its forward end to the lower face of the leather shank piece 28, which is relatively thin and appreciably narrower than the corresponding section of the insole 10. The longitudinal edges 34, 36 of shank piece 28 may be skived, and, as shown in Figs. 3, 4 and 5, lie well inwardly of the approximately parallel edges of insole 10.

15 A rounded forward end 38 of piece 28 is covered on its underside by the generally coextensive head portion 13 of member 12, is positioned below the metatarsal arch area of insole 10, and cooperates with the resilient pad 30 in a manner now 20 to be described. Pad 30 is adhesively secured to the upper face of shank piece 28, and is coextensive with that portion of its upper face which extends from a point adapted to lie beneath the middle cuneiform to just short of its forward end 38. Preferably pad 30 is of fine 25 sponge rubber, with skived edges merging with the shank piece 28. Its flat underface 40 is given the longitudinal curve of the stiffener 26, but its upper face 42 is convexed as shown by Fig. 1 and the section of Figs. 2, 3, 4 and 5 in which the superimposed portion of insole 10 is of a corresponding shape. This shape may be produced by molding the insole 10 on a last having a complementary recess and also provided with a 30 convexity for cupping the heel area.

If the inner cookie or insole extension 44 of the Fig. 8 modification is made a part of the otherwise similar insole 100, it too will be molded to shape on the last. The cookie 44 may be of leather; and it is positioned to extend from a short distance rearward of the middle of the inner edge of the heel portion of the insole 100 to a short distance past the center of the corresponding edge of the shank portion. At its lower edge 46 it is suitably secured to the insole 100, e. g., by a cement; and its upper edge 48 is convexed, as shown.

The cookie or wing 44 assists heel lift 22 in preventing inward rotation of the os calcis and helps to preserve the scaphoid-internal cuneiform articulation.

The insole 10 of Figs. 1 to 5 obviously is adapted for use in any type of shoe construction where a sewing channel is not required, for example, McKay, cement, or stitch-down. Without modification, it can also be added as a slip insole to any completely assembled shoe.

However, the insole 100 in the Fig. 8 modification is channeled, as indicated by the reference numeral 103, for attachment to a welt 105 of the illustrated welt shoe construction 106. Although not shown, it is to be understood that the margins of the member 120, covering the shank of the insole, will be channeled to provide continuations of the insole channel 103. The cookie 44 may be secured to the upper 107 of welt shoe 106 in any conventional manner.

A man's shoe has been shown for purposes of illustration, but the principles of this invention 70 can be adapted readily to a woman's shoe by the skilled worker in this art.

The insole construction of this invention produces a balanced shoe which causes a foot to function in a normal way and insures the continued function in a normal manner of an un-

5 distorted foot. The various features which have been described in detail act in combination to retain the heel of a wearer against sliding relative to the shoe insole, to prevent rotation of the forward end of the os calcis, to maintain the inner longitudinal arch of a foot by elevating the specified bones adjacent the os calcis, to maintain the bones on the opposite side of a foot in proper alignment, and to preserve the shape of the metatarsal arch of a foot so that it will not spread 10 and cause uncomfortable impingement at the metatarsal heads. As hitherto noted, downward deflection of the longitudinal arch is resiliently resisted and sliding friction further obviated.

15 Although many variations from the foregoing embodiment will be apparent, the scope of the invention is to be limited only by the appended claims.

Having thus described my invention, what I 20 claim as new and desire to secure by Letters Patent of the United States is:

1. As part of a shoe construction, an insole having a cupped heel portion which is of greatest elevation at its inside to prevent rotation of the os calcis in that direction, an upwardly arched forward heel and shank portion which is higher at its inside edge to conform to the inner longitudinal arch cavity of a foot, and an upwardly convexed portion extending intermediate the insole edges for substantially the 30 length of the innersole shank for preserving the shape of the metatarsal arch of a foot; means for resiliently resisting flattening of the upwardly arched shank and heel portions of the innersole; and means underlying the upwardly convexed 35 portion, and intermediate the insole edges, for maintaining its shape.

2. In a welt shoe, a channeled innersole having a cupped heel portion which is of greatest elevation at its inside to prevent rotation of the os 40 calcis in that direction, an upwardly arched forward heel and shank portion which is higher at its inside edge to conform to the inner longitudinal arch cavity of a foot, and an upwardly convexed portion extending intermediate the insole edges for substantially the length of the shoe shank for preserving the shape of the metatarsal arch of a foot; stiffener means for resiliently resisting flattening of the upwardly arched shank and heel portions of the innersole; and 50 resilient cushion means underlying the upwardly convexed portion, and intermediate the inner sole edges, for maintaining its shape.

3. The combination comprising an insole of 55 normal outline and substantially uniform thickness having a cupped heel portion which is of greatest elevation at its inside to prevent rotation of the os calcis in that direction, an upwardly arched forward heel and shank portion which is higher at its inside edge to conform to the inner longitudinal arch cavity of a foot, and an upwardly convexed portion extending intermediate the insole edges for substantially the length of the innersole shank for preserving the shape of the metatarsal arch of a foot; metallic shank 60 stiffener means for resiliently resisting flattening of the upwardly arched shank and heel portions of the insole; and resilient means underlying the upwardly convexed portion, and also intermediate the insole edges, for maintaining its 65 shape.

4. The combination comprising an insole of 70 normal outline having a cupped heel portion which is of greatest elevation at its inside to prevent rotation of the os calcis in that direction,

an upwardly arched forward heel and shank portion which is higher at its inside edge to conform to the inner longitudinal arch cavity of a foot, and an upwardly convexed portion extending intermediate the insole edges for substantially the length of the innersole shank for preserving the shape of the metatarsal arch of a foot; a flexible wing member extending from the inner edge of the insole and arranged to support the scaphoid-internal cuneiform articulation of a wearer's foot; means for resiliently resisting flattening of the upwardly arched shank and heel portions of the insole; and means underlying the upwardly convexed portion, and also intermediate the insole edges, for maintaining its shape.

5. The combination comprising an insole; a sheet member secured to the underside of the insole and covering the entire shank and a portion of the heel thereof; a shank comprising a longitudinally arched stiffener, a shank piece, and a longitudinally and transversely convexed resilient pad all intermediate the insole and the sheet member; and a wedge-shaped heel lift underlying the heel of the insole on its inner side and tapering toward its longitudinal axis, said insole being cupped on its upper heel surface, longitudinally arched at its shank, and generally convex in the area over the resilient pad of the shank, which pad extends longitudinally of the insole and inwardly of its edges from the front portion of the heel area to the metatarsal arch area, whereby the cupped heel portion of the insole prevents the foot of a user from sliding forward, the heel lift elevates the forward end of the os calcis and prevents it from rotating, the arched shank of the insole limits downward flexing of the longitudinal arch, and the convex portion overlying the resilient pad of the shank serves to preserve the shape of the metatarsal arch.

6. A welt shoe which includes a channeled innersole; a sheet member secured to the underside of the innersole and covering the entire shank and a portion of the heel thereof; a shank comprising a longitudinally arched stiffener, a shank piece, and a longitudinally and transversely convexed resilient pad in the order recited between the innersole and sheet member; and a wedge-shaped heel lift underlying the heel of the innersole on its inner side and tapering toward its longitudinal axis, said innersole being cupped on its upper heel surface, longitudinally arched at its shank, and generally convex in the area over the resilient pad of the shank, which pad extends longitudinally of the innersole and inwardly of its edges from the front portion of the heel area to the metatarsal arch area, whereby the cupped heel portion of the innersole prevents the foot of a user from sliding forward, the heel lift elevates the forward end of the os calcis and prevents it from rotating, the arched shank of the innersole

limits downward flexing of the longitudinal arch, and the convexed portion overlying the resilient pad of the shank serves to preserve the shape of the metatarsal arch.

7. The combination comprising an insole; a sheet member secured to the underside of the insole and covering the entire shank and a portion of the heel thereof; a shank comprising a longitudinally arched stiffener, a shank piece, and a longitudinally and transversely convexed resilient pad all intermediate the insole and the sheet member; and a wedge-shaped heel lift underlying the heel of the insole on its inner side and tapering toward its longitudinal axis, said insole being cupped on its upper heel surface, longitudinally arched at its shank and generally convex in the area over the resilient pad of the shank, which pad extends longitudinally of the insole and inwardly of its edges from the front portion of the heel area to the metatarsal arch area, and having a cookie extension projecting from its arched inner edge whereby the cupped heel portion of the insole prevents the foot of a user from sliding forward, the heel lift elevates the forward end of the os calcis and prevents it from rotating, the arched shank of the insole limits downward flexing of the longitudinal arch, the convex portion overlying the resilient pad of the shank serves to preserve the shape of the metatarsal arch, and the cookie extension aids in the preservation of the scaphoid-internal cuneiform articulation.

8. The combination comprising an insole; a sheet member secured to the underside of the insole and covering the entire shank and a portion of the heel thereof, said member having a forwardly extending head portion; a shank comprising a longitudinally arched metal stiffener, a shank piece having its forward end under the head portion of the sheet member, and a longitudinally and transversely convexed rubber pad all intermediate the insole and the sheet member; and a wedge-shaped resilient heel lift underlying the heel of the insole on its inner side and tapering toward its longitudinal axis, said insole being cupped on its upper heel surface, longitudinally arched at its shank and generally convex in the area over the rubber pad of the shank, which pad extends longitudinally of the insole and inwardly of its edges from the front portion of the heel area to the metatarsal arch area, whereby the cupped heel portion of the insole prevents the foot of a user from sliding forward, the heel lift elevates the forward end of the os calcis and prevents it from rotating, the arched shank of the insole limits downward flexing of the longitudinal arch, and the convex portion overlying the resilient pad of the shank serves to preserve the shape of the metatarsal arch.

JOHN LAWANDUS. 60
